UNITED STATES PATENT OFFICE.

GEORGE DARLOW, OF WINFRED TOWNSHIP, LAKE COUNTY, SOUTH DAKOTA.

BUNDLE-LOADER.

1,145,752.

Specification of Letters Patent.

Patented July 6, 1915.

Application filed October 31, 1914. Serial No. 869,656.

To all whom it may concern:

Be it known that I, GEORGE DARLOW, a citizen of the United States, residing in Winfred township, in the county of Lake and State of South Dakota, have invented certain new and useful Improvements in Bundle-Loaders, of which the following is a specification.

This invention relates to harvesting devices for handling grain in sheaves, and has broadly for its object the provision of an improved device adapted to be drawn over a field after the grain has been cut and tied in bundles and which will pick up the bundles and load them into a wagon traveling beside the device.

An important object is the provision of a loader of this character provided with a novel pick up cylinder embodying movable teeth and automatic operating mechanism for protecting the teeth to engage the bundles and for retracting the teeth out of engagement therewith at a predetermined time.

Another object is the provision of a loader of this character having means operated by the driver for raising the pick up cylinder considerably above the ground to avoid obstructions such as stones or stumps which would injure the mechanism.

Still another object is the provision of a novel and peculiar construction whereby the portion of the frame supporting the pick up cylinder may be quickly moved by the driver relatively to the main frame to permit changing the driving gears for changing the speed of rotation of the pick up cylinder relatively to the speed of travel of the loader, and whereby the device may be thrown quickly out of gear while traveling.

A further object is the provision of means for discontinuing the discharge of bundles when the receiving wagon is unable to keep in proper relation with the loader as in following a crooked row or making a turn or curve, and at the same time have the pick up cylinder and the receiving conveyer continue operating and the discharge conveyer receive and hold the bundles until the wagon is in a position to receive them.

Other objects and advantages residing in the details of structure together with comparative simplicity, ease of operation, efficiency in service, and the general improvement of the art will be carefully brought out in the following description and illustrated in the accompanying drawings, in which:

Figure 1 is a top plan view of the loader, Fig. 2 is a side elevation with the front drive wheel removed, Fig. 3 is a rear elevation, Fig. 4 is a fragmentary elevation of the opposite side, Fig. 5 is a cross sectional view on the line 5—5 of Fig. 1, and Fig. 6 is a sectional view on the line 6—6 of Fig. 5.

Referring more particularly to the drawings, the numeral 1 designates the longitudinal bars of the main or rigid frame which are provided upon their forward ends with bearing blocks 2 journaly receiving the main or drive axle 3 carrying the traction wheels 4 provided with the usual ratchet hubs. The bars 1 support a platform 5 upon the rear end of which are revoluble standards 6 carrying axles 7 provided with wheels 8. An auxiliary or driver's platform 9 is supported above the main platform 5 by standards 10 and carries the usual seat 11.

The movable frame comprises bars 12 and 13 spaced apart as shown and formed separately or integrally by bending, and in either case channel bars being preferably used. Bearing blocks 14 are slidably disposed between the bars 12 and 13 and journaly receive the axle 3, while other bearing blocks 15 are rigidly secured between these bars and journaly receive the axle 16 of the pick up cylinder 17.

The pick up cylinder 17 comprises outer heads 18 formed as sprockets and an intermediate disk 19, all secured upon the axle 16. A plurality of rods 20, 21, 22 and 23 extend through the heads 18 and the disk 19, and carry upon their respective ends, pinions 24, 25, 26 and 27, each having preferably eight teeth. A cylindrical housing 28 is secured upon the bars 12 and 13 concentric with the axle 16 and has secured upon its inner periphery a ring 29 provided with sets of teeth 30, 31 and 32, the set 30 comprising four

teeth and the sets 31 and 32 comprising each two teeth. These sets of teeth are adapted to mesh with the pinions 24, 25, 26 and 27 at different stages of rotation of the pick up cylinder as will be hereinafter more fully described. The rods 20, 21, 22 and 23 carry a plurality of fingers 33 adapted to engage bundles of grain and lift them from the ground. The relative positions of the pinions, sets of teeth on the ring 29, and fingers should be as shown in Fig. 6. The pick up cylinder 17 is rotated by means of gears 34 on the drive axle 3 meshing with gears 35 on the cylinder shaft 16.

15 As the cylinder 17 rotates, the rods 20, 21, 22 and 23 will be carried around with it carrying the fingers 33. The rods and fingers being adjusted in the first place to occupy the relative positions shown, as the 20 rods 20, 21, 22 and 23 approach the downward limit of their movement, the pinions will successively engage the teeth 32 and be rotated a quarter turn moving the rods 20, 21, 22 and 23 so that the fingers 33 will 25 extend substantially horizontally forward. As the rods then approach the lower forward limit of their movement, the pinions will engage the teeth 31 and be moved another quarter turn to still extend in the 30 same position relative to the ground. In these two positions the fingers 33 will engage bundles of grain and carry them up. As the rods approach the upper forward limit of their movement, the pinions will 35 successively engage the teeth 30 and be rotated a half turn, thereby causing the fingers to swing down out of engagement with the bundles, thus allowing the bundles to fall upon the receiving conveyer designated 40 as a whole by the numeral 36. As the rods are moved to their upper rearmost positions they will retain their preceding positions, that is they will hang straight down. As the rods then approach their lowest rear 45 positions the pinions will engage the teeth 32, thus moving the rods and consequently the teeth as first described.

In order that the rods may be prevented 50 from undesired movement and still be allowed to move at the proper time, I provide upon each rod a spider 37 comprising preferably four arms carrying upon their ends rollers 38 engaging against the inner periphery of the housing 28 and preventing 55 the rods from rocking. In order that the rods may be permitted to rock at the proper time, I provide depressions 39 in the periphery of the housing adjacent the sets of teeth 30, 31 and 32, so that as the pinions 60 engage each set of teeth the rollers will enter the depressions and allow the rods to turn.

The receiving conveyer 36 onto which the bundles are deposited comprises a pair of 65 rearwardly inclined bars 40 bolted upon the

bars 12 and braced by bars 41 as shown. Bearings 42 are secured upon the bars 40 and journally receive a shaft 43 carrying at its center a pulley or roller 44 and at its ends sprockets 45. Chains 46 are trained about the sprockets 18 and 45 and a belt 47 is trained about the rollers 19 and 44. Slats 48 are secured upon the chains and belt and are preferably provided with spikes 49 adapted to penetrate the bundles which are 55 deposited upon the conveyer. As the pick up cylinder 17 rotates, the conveyer 36 will be driven by virtue of the sprocket and chain connection.

The discharging mechanism comprises a 80 hopper 50 secured upon the platform 5 rearwardly of the conveyer 36 and leading to a chute 51 containing a spiked and slotted conveyer 52 inclined upwardly for discharging bundles into a suitable wagon 85 traveling beside the loader. The shafts 53 and 54 at the ends of the conveyer 52 are provided with sprockets 55 and 56 about which is trained a chain 57. The sprocket 56 is loose upon the shaft 54 and has formed thereon a clutch member 58 engaging a clutch member 59 splined upon the shaft 54. The two clutch members are held normally in engagement by a spring 60 surrounding the shaft 54 and abutting against 95 the clutch member 59 and a bearing 61. The clutch member 59 has a sprocket 62 formed thereon about which is trained a chain 63 trained about a sprocket 64 secured upon a short shaft 65 journaled in a bearing 66 secured upon the platform 5. The sprocket 64 has formed thereon a bevel gear 67 which meshes with a crown gear 68 secured upon the lower end of an inclined shaft 69 journaled through a bearing 100 70 secured upon the hopper 50. The upper end of the shaft 69 is connected by a universal joint 71 with the lower end of a square shaft 72 upon which is slidably mounted a bevel gear 73 meshing with the 105 bevel gear 74 secured upon one end of the shaft 43. A bracket 75 is secured upon the adjacent bar 40 and extends under the bevel gear 73 for holding it in mesh with the gear 74.

The loader is drawn by horses hitched to whiffletrees 76 connected with a draw beam 77 bolted onto the platform 5, one horse being used on each side of the machine. As the loader is drawn over a field, the bundles of grain will be picked up by the cylinder 17 and deposited onto the conveyer 36 as previously described. The bundles will fall from the top of the conveyer 36 into the hopper 50 and consequently onto the conveyer 52 which is driven by the gears 74 and 73, shafts 72 and 69, gears 68 and 67, chain 63, clutch members 59 and 58, and chain 57. The bundles will be carried upwardly by the conveyer 52 and dumped 130

into a suitable wagon traveling beside the device.

In making turns it is naturally impossible for a wagon to maintain its proper place beside the machine to receive bundles picked up. In order to permit the loader to continue to pick up bundles and hold them against discharging until the wagon can resume its place, I provide a foot pedal 78 located at the front edge of the driver's platform 9 in a position convenient to his foot, and on the upper end of a lever 79 pivoted at 80 upon a bracket 81 connected with one of the standards 10 and braced by a rod 82. The lower end of the lever 79 is forked and disposed in a groove 83 in the clutch member 59. When the driver pushes the pedal 78 forward, the clutch member 59 will be moved back against the resistance of the spring 60 and out of engagement with the clutch member 58, thus rendering the conveyer 52 inoperative and allowing bundles picked up to be retained in the hopper 50. When the accompanying wagon has resumed its proper place, the pedal 78 is released, whereupon the conveyer 52 will again operate to discharge the bundles.

When the driver sees that there are obstructions in front of the machine which might cause injury, it is necessary that the pick up cylinder be raised to avoid the obstructions. In order to accomplish this, I provide a pair of rearwardly extending links 84 pivotally connected with the bars 40 and connected at their rear ends by a rod 85. A lever 86 is pivoted at its lower end as shown at 87 to a bracket 88 mounted on the beam 77 and is connected intermediate its ends with the rod 85, the upper end being adjacent the platform 9 convenient to the driver. When the lever 86 is pulled back, the movable frame comprising the bars 12 and 13 and supporting the conveyer 36 will be tilted backwardly, the bearing blocks 14 pivoting upon the axle 3. When this is done the bevel gear 74 will force the gear 73 downwardly along the shaft 72 while both gears remain continually in mesh, the universal joint 71 permitting rearward swinging of the shaft 72 while retaining its operative connection with the shaft 69. When the obstructions have been passed over the lever 86 is released, whereupon the movable frame will return to its original position and the bracket 75 will pull the gear 73 upwardly upon the shaft 72 holding it in mesh with the gear 74.

In order to throw the entire device out of gear and to permit changing the relative sizes of the gears 34 and 35, I provide below the platform 5 a yoke 89 having its longitudinal arms 90 pivotally connected at 91 with the movable frame comprising the bars 12 and 13. The transverse portion 92 of the yoke is provided with a threaded hole

for the reception of a screw 93 formed on a shaft 94 mounted in bearings 95 below the platform 5. A sprocket 96 is secured on the shaft 94 and has trained thereover a chain 97 which extends upwardly and about 70 a sprocket 98 mounted on a shaft 99 journaled through a standard 100 bolted on the platform 9. The shaft 99 is provided with a crank handle 101. When the handle 101 is turned to the left the screw 93 will thread 75 out of the hole in the transverse yoke bar 92 and move the yoke and the movable frame forward upon the bearing blocks 14, thereby disconnecting the gears 35 and 36 and rendering the entire machine inoperative. 80 When this is done other sizes of gears may be substituted for the gears 34 and 35 for changing the speed of rotation of the cylinder 17 relatively to the speed of travel of the machine.

In order to guide bundles of grain to the pick up cylinder 17 I form the frame bars 12 long and curve them outwardly as shown at 102.

The draft animals are prevented from injury from contact with the wheels 4 by means of fender rods 103 secured upon the guide portions 102 and extending rearwardly outwardly of the wheels 4.

Having thus described my invention what I claim is:

1. In a bundle loader having a main frame supported on wheels, a movable frame comprising channel bars bent substantially U-shape with their upper free end extending beyond the lower free end, bearing blocks slidably disposed in said movable frame to journally receive the drive axle, a second set of bearing blocks rigidly secured in said frame, a pick up cylinder mounted in said 100 movable frame, said cylinder being journaled in said second set of bearing blocks and means for swinging said movable frame upwardly to avoid obstructions.

2. In a bundle loader having a main 110 frame, a movable frame comprising channel bars bent substantially U-shape and having the free ends of their upper portions extend beyond the free ends of their lower portions, bearing blocks slidably disposed 115 in said movable frame to journally receive the drive axle, a second set of bearing blocks rigidly secured in said frame, a pick up cylinder journaled in said last named bearing blocks, and a yoke pivotally connected with 120 said movable frame, a threaded shaft mounted in the transverse portion of said yoke, and means for operating said shaft to move said frame forward to disengage the driving gears and said frame rearward to engage 125 said gears.

3. A bundle loader comprising a main frame supported upon driving wheels, a movable frame slidably mounted in relation to said main frame, a pick up cylinder and re- 130

ceiving conveyer on said movable frame, gears on said driving wheels meshing with gears on said cylinder, and means for moving said movable frame to disconnect said 5 gears, said means comprising a yoke having its longitudinal arms pivotally connected with said movable frame and having a threaded hole in its transverse portion and a threaded shaft mounted in said hole and 10 connected with a crank mechanism, by sprockets and chain.

4. A bundle loader comprising a main frame supported upon driving wheels, a movable frame slidably mounted in relation to 15 said main frame, a pick up cylinder and receiving conveyer on said movable frame, gears on said driving wheels meshing with gears on said cylinder, and means for moving said movable frame to disconnect said 20 gears, said means comprising a yoke connected with said movable frame and extending along said main frame, and screw actuated means for moving said yoke.

5. A bundle loader comprising a main 25 frame supported upon driving wheels, a movable frame slidably mounted in relation to said main frame, a pick up cylinder and receiving conveyer on said movable frame, gears on said driving wheels meshing with 30 gears on said cylinder, and means for moving said movable frame to disconnect said gears, said means comprising a yoke connected with said movable frame and extending along said main frame, a screw revolute 35 upon said main frame and having threaded engagement with said yoke, and means for rotating said screw.

6. A bundle loader comprising a main frame supported upon driving wheels, a 40 movable frame slidably mounted in relation to said main frame, a pick up cylinder and receiving conveyer on said movable frame, gears on said driving wheels meshing with 45 gears on said cylinder, and means for moving said movable frame to disconnect said gears, said means comprising a yoke connected with said movable frame and extending rearwardly along said main frame, a screw revolute upon said main frame and 50 having threaded engagement with said yoke, a sprocket on said screw, a second sprocket provided with a crank handle disposed convenient to the driver, and a chain trained about said sprockets.

55 7. A bundle loader comprising a main frame, an axle journaled therethrough and carrying driving wheels, a second frame comprising pairs of spaced bars straddling said axle, bearings receiving said axle and 60 slidably disposed between said spaced bars, a pick up cylinder on said second named frame, gears on said axle meshing with gears on said cylinder, and means for moving said second named frame to disconnect said 65 gears, said means comprising a yoke con-

nected with said second named frame and a manually operated screw revolute upon said main frame and engaging said yoke.

8. A bundle loader comprising a main frame supported upon an axle carrying driving wheels, a second frame pivoted in relation to said main frame, a bundle pick up cylinder journaled in said movable frame, gear connections between said axle and said pick up cylinder, a receiving conveyer on 70 said second named frame and driven by said cylinder, a discharge conveyer on said main frame receiving bundles from said receiving conveyer, a bevel gear on the upper shaft of said receiving conveyer, a shaft on said main frame, a sprocket on said shaft, a sprocket on the lower shaft of said discharge conveyer, a chain trained about said sprockets, a bevel gear on said second named shaft, a 75 shaft on said main frame, a gear on said last named shaft meshing with said second named gear, a square shaft having a universal joint connection with said last named shaft, a bevel gear on said square shaft meshing with said first named gear, and a 80 bracket on said second named frame holding said first and last named gears in mesh, said second named frame being tiltable to elevate said pick up cylinder and the driving connection between said receiving and 85 discharge conveyers being continuous.

9. In a bundle loader, a bundle pick up cylinder comprising heads, a plurality of rods connecting said heads, bundle engaging fingers on said rods, pinions mounted on the ends of said rods, spider members comprising four points provided with roller bearing faces mounted adjacent the ends of said rods, a fixed ring surrounding the ends of said rods and means on its inner periphery for partially rotating said rods at predetermined intervals for extending and retracting said fingers.

10. In a bundle loader, a bundle pick up cylinder comprising heads, transverse rods connecting said heads, bundle engaging fingers on said rods, pinions on said rods, and a fixed ring provided with sets of teeth engageable by said pinions at predetermined intervals for partially rotating said rods with the consequent extension and retraction of said fingers.

11. In a bundle loader, a bundle pick up cylinder comprising a plurality of heads, transverse rods connecting said heads, bundle engaging fingers on said rods, pinions on said rods, a fixed ring having sets of teeth thereon engaging said pinions at predetermined intervals for partially rotating said rods, and means for preventing rotation of said pinions except at said intervals.

12. In a bundle loader, a bundle pick up cylinder comprising heads, transverse rods connecting said heads, bundle engaging fingers on said rods, pinions on said rods, a 120

ring having sets of teeth engaged by said pinions at predetermined intervals for partially rotating said rods with the consequent extension and retraction of said fingers, a cylindrical housing, and members carried by said rods and bearing against said housing for normally preventing rotation of said pinions, said housing being provided with depressions to permit the en-

trance of said members when said pinions engage said teeth, whereby said rods may be allowed to partially rotate.

In testimony whereof I hereto affix my signature in the presence of two witnesses.

GEORGE DARLOW.
